AUTOMATIC SWITCH CONTROL SYSTEM FOR CLASSIFICATION YARDS

Stuart M. Phelps, Rochester, N. Y., assignor to General Railway Signal Company, Rochester, N. Y.

Application November 12, 1953, Serial No. 391,547

7 Claims. (Cl. 246—134)

This invention relates to switch control systems for railway classification yards, and it more particularly pertains to switch control systems in which a route is automatically selected for each car, or cut of cars, subsequent to the manual designation of the track destination for that car or cut of cars.

Such a system is disclosed in the prior U. S. Patent No. 2,194,353, granted to N. C. L. Brown et al., March 19, 1940, and in the prior U. S. application of F. W. Brixner, et al., Ser. No. 179,462, filed August 15, 1950, now U. S. Patent 2,700,728 granted January 25, 1955. In systems of this nature, route description storage relays are provided for the different track switches, and the route description that is designated for each car or cut of cars is transferred from one route storage to the next as the car progresses from track switch to track switch. This transfer is caused by the dropping away of the track relay for the detector track section of the associated track switch. The track circuits for these track relays are fed by alternating current supplied by the power utility company of the area, while the route description storage relays are operated by direct current from a battery. The alternating current track circuits, as compared to direct current track circuits, are desirable to provide higher shunting sensitivity.

Because of the possibility of power interruption of the alternating current source from time to time, a standby motor generator auxiliary alternating current supply is generally provided so that it is available upon failure of the normal source of alternating current. The time required for the auxiliary supply to take over is such as to permit the momentary dropping away of all track relays, with the resultant undesirable transfer of route descriptions.

The system according to the present invention provides that the standby source of alternating current can be normally inactive and started only when needed. Thus, the standby motor generator can be started by the dropping away of a conventional power-off relay, for example. This is made possible by the provision of a relay conveniently called a power detector relay, that is energized by the alternating current power that is feeding the track circuits, whether it be the normal alternating current source or the standby alternating current source. This relay is preferably made quicker to drop away and slower to pick up than the track relays.

Contacts of the power detector relay are used in the transfer circuits for the storage relays associated with the different track switches to prevent transfer and cancellation of storages when the track relays are momentarily dropped away during the time interval required for the starting of the standby motor generator. When the track relays have had time to be restored to their normally energized positions by the standby energy, the power detector relay is restored to its normally energized position, and the route storage means is again subject to transfer and cancellation upon the dropping away of the track relays by the shunting of their respective track circuits.

2

An object of the present invention, is to prevent transfer of route description storages when the track relays drop away because of an interruption of alternating current power feeding the track circuits.

5 Another object of the present invention is to prevent cancellation of route description storages when the track relays drop away because of an interruption of power feeding the track circuits.

Other objects, purposes, and characteristic features of 10 the present invention will be in part obvious from the accompanying drawings and in part pointed out as the description of the invention progresses.

In describing the invention in detail, reference is made 15 to the accompanying drawings in which similar reference characters are used to designate corresponding or associated parts, and in which:

Fig. 1 is a diagram of the track layout of a typical classification yard for this embodiment of the present invention;

Figs. 2A, 2B and 2C, when placed side by side, illustrate 20 an automatic switching control system for the track layout illustrated in Fig. 1; and

Fig. 3 illustrates the manner in which the power detector relay prevents cancellation upon a power interruption of the alternating current power supply of the route description storage for the last track switch in a route.

The circuits illustrated are prepared more particularly 30 to facilitate an understanding of the mode of operation of the system and the principles involved, rather than to illustrate the specific construction and arrangement of parts that would be employed in practice. The symbols (+) and (—) have been used to indicate the respective positive and negative connections to suitable batteries or other sources of direct current, and the symbols (BX) and (NX) have been used to indicate connections to the 35 instantaneous positive and negative terminals of a source of alternating current such as might be provided by a power utility company.

With reference to Fig. 1, the hump yard layout for 40 this embodiment of the present invention comprises classification tracks that are connected through various track switches W to a single stretch of track extending over a hump. It is to be understood that the present invention is adaptable for practically any hump classification yard to be encountered in practice, and the simple 45 yard illustrated is to be considered to in no way limit the scope of the present invention. As is illustrated by the vertical dotted lines associated with the letters A, B, C, and D, the track switches are divided into four groups A, B, C, and D for route description purposes, the track 50 switch 8W being in Group A, the track switches 3W and 12W being in group B, the switches 5W and 10W being in group C, and the switches 2W, 4W, 6W, 7W, 9W and 11W being in group D.

The track equipment is provided according to usual 55 practice in classification yards of this character, the track switches W being operated by suitable power switch machines SM, and each of the track switches W having associated therewith a detector track section T that is fed by alternating current in a manner comparable to that 60 illustrated in Fig. 2A for the feeding of the track circuit 8T associated with the track switch 8W.

In accordance with usual classification yard practice, a hump conductor station is provided near the hump, and located at that station is a suitable control panel such as 65 the panel P illustrated in Fig. 2A. This panel has a push button PB for each of the classification tracks as a means by which the hump conductor can designate the destinations for the respective cars and cuts of cars.

The route descriptions set up in response to the actuation 70 of the push buttons PB can be provided in any suitable manner such as by the organization disclosed in the above mentioned prior Brown et al. Patent No. 2,194,353

or in the above mentioned prior application of F. W. Brixner et al., Ser. No. 179,462 filed August 15, 1950, now U. S. Patent 2,700,728 granted January 25, 1955. For the purpose of simplification of the drawings for this embodiment of the present invention, certain elements of the system organization that have been taught by prior disclosures are illustrated in block form, some circuits being shown in detail in order to make clear how the present invention is applied to these prior teachings of automatic switching control systems.

With reference to Fig. 2A, a route description storage unit 8S3 is illustrated as being fed by route descriptions designated by operation of the push buttons PB on the hump conductors panel P. This storage unit is adapted to transfer its storage over wires a, b, c, and d to a storage unit 8S2 when this unit is available for reception of a route description.

The storage relay bank and associated control apparatus that is more directly associated with the track switch 8W is shown in detail, the relays 8ACS1, 8BCS1, 8CCS1 and 8DCS1 constituting this bank of storage relays, and relays 8TN1 and 8SD1 are associated therewith for the purpose of governing the delivery of route description storage from the storage 8S2 to this bank of storage relays. Transfer and storage control relays 3-5TN2 and 3-5SD2 (see Fig. 2B) are provided for governing the transfer of the route storage of relays 8BCS1, 8CCS1 and 8DCS1 to a storage unit 3-5S2 (see Fig. 2C) that is associated with the track switches 3W and 5W. Similarly, the relays 10-12TN2 and 10-12SD2 are provided for governing transfer of the route description stored by relays 8BCS1, 8CCS1 and 8DCS1 to a storage unit 10-12S2.

Normal and reverse switch position indicating relays are provided for the various track switches. Relays 8NWP and 8RWP, for example, are provided for the track switch 8W. These relays repeat the respective normal and reverse positions of track switch 8W by their selective energization.

Relays 8TNP, 8TN1, 8CN1 and CN are provided for purposes of governing cancellation of a route description stored by the relays 8ACS1, 8BCS1, 8CCS1, and 8DCS1.

The track circuits are normally fed from the power utility system source of alternating current for the area, and a standby alternating current power supply is provided in the form of alternating current generator ACG which is driven when standby power is needed by a motor M. A power off relay PO is provided for switching from the normal source of alternating current energy to the standby source and vice-versa.

A track relay TR is provided for each of the track circuits and is operated through a suitable full-wave rectifier in a manner typically illustrated for the operation of the track relay 8TR from the track circuit 8T.

A power detector relay PD is provided for preventing transfer and/or cancellation of route descriptions during the changeover from one source of power to the other in a manner to be more readily apparent as the description progresses. This relay is preferably made quicker to drop away and slower to pick up than the track relays TR by the inclusion in its control circuit of a suitable resistor R.

With reference to Fig. 3, certain relays TR, CN, SD1 and PD are illustrated. These relays are provided for purposes comparable to those described for relays bearing similar reference characters that are associated with the track switch 8W.

Contact have been illustrated of suitable manual switch control levers 8SML and 2SML, and it is to be understood that these switch control levers are of the three positioned type, and in addition, the contacts illustrated are subject to being opened by the pulling out of the associated lever against the action of a biasing spring, these contacts being used for the purpose of cancellation in a manner which has been pointed out in the above mentioned Brixner et al. application.

Having considered the general organization of apparatus provided in the switch control system of one embodiment of the present invention, more specific consideration of the system will now be given with reference to the mode of operation upon consideration of typical operating conditions.

Operation

Although reference is to be made to the above mentioned Brixner et al. application for a detail description of the automatic switching organization, a brief consideration will now be given as to the mode of operation of the automatic switching system as illustrated, partly by block diagram, in Figs. 2A, 2B and 2C.

As is indicated by the dotted line 20 of the block diagram (see Fig. 2A), the actuation of a push button PB on the hump conductors push button panel P sets up a route description storage in the storage unit 8S3 (assuming this unit is available to receive the route description) comprising four characters for the respective groups of track switches A, B, C and D (see Fig. 1). Route storage relays (not shown) are provided in this storage unit for these four characters comparable to the respective storage relays 8ACS1, 8BCS1, 8CCS1 and 8DCS1 which are provided for another storage unit. Each of these storage relays is selectively picked up or left in its dropped-away position in accordance with whether a track switch in the associated respective A, B, C, or D group is required to be in its normal or reverse position for the route that has been designated.

Assuming that no prior route description is stored for the track switch 8W, the route storage is immediately transferred over wires a, b, c, and d to a similar storage unit 8S2, and from the storage unit 8S2, the route description is transferred over wires a1, b1, c1, and d1, to the storage bank comprising the relays 8ACS1, 8BCS1, 8CCS1, and 8DCS1. This transfer is effective in accordance with the picking up of transfer relays 8TN1 and 8SD1 by the energization of circuits that have been described for the energization of similarly identified relays in the above mentioned Brixner et al. application. Relay 8SD1 (see Fig. 2A) is maintained picked up by a stick circuit extending from (+), including front contacts 21 and 22 of relays 8TN1 and 8SD1 connected in multiple, wire 23, back contact 24 of relay 3-5TN2, back contact 25 of relay 10-12TN2, back contact 26 of relay 8DP, wire 27, contact 28 of lever 8SML in its normal position, back contact 29 of relay CN, back contact 30 of relay 8CN1, and winding of relay 8SD1, to (-). This stick circuit also includes back contact 31 of the track relay 8TR connected in multiple with back contact 26 of relay 8DP. Relay 8ACS1 is effective, with relay 8SD1 in its picked up position, to govern the operation of the track switch 8W to its normal or reverse position in accordance with whether back contact 32 or front contact 32 of relay 8ACS1 is closed. With relay 8SD1 in its picked up position, stick energy is applied through front contact 33 to maintain the code storage relays 8ACS1, 8BCS1, 8CCS1 and 8DCS1 in their selected positions according to the route description code which is being stored.

The track relay 8TR is associated with the detector track section 8T for the track switch 8W and is connected to the track rails through a full wave rectifier 34. The track circuit is normally fed through front contacts 35 and 36 of the power off relay PO from a conventional utility source of alternating current having its terminals designated as (BX) and (NX). All other track circuits are also fed through these contacts 35 and 36 of the power off relay PO.

When the detector track section 8T becomes occupied by a car for which the route description is stored by the relays 8ACS1, 8BCS1, 8CCS1 and 8DCS1, transfer of route description storage is made to another storage unit as selected by the position of the track switch 8W. If the track switch 8W is in its normal position at this time,

transfer will be made to the storage unit 3-5S2 (see Fig. 2C) in accordance with the energization of the transfer relays 3-5TN2 and 3-5SD2, the relay 3-5SD2 being energized by a circuit (not shown) similar to the circuit illustrated for relay 8SD1. The circuit by which the relay 3-5TN2 is energized at this time extends from (+), including front contact 37 (see Fig. 2A) of relay PD, back contact 38 of relay 8TR, front contact 39 of relay 8SD1, back contact 40 of relay 8TN1, back contact 41 of relay 8TNP, front contact 42 of relay 8ACS1, wire 43, front contact 44 of relay 8NWP, back contact 45 of relay 3-5SD2, and winding of relay 3-5TN2, to (-). The picking up of this relay closes a stick circuit for maintaining relay 3-5TN2 picked up extending from (+), including front contact 46 of relay 8SD1 (see Fig. 2A), wire 47, front contact 48 of relay 3-5TN2 and winding of relay 3-5TN2, to (-).

The picking up of relay 3-5TN2 causes the picking up of the relay 3-5SD2 by the energization of a circuit (not shown) similar to the circuit shown for relay 8SD1 and in a manner fully described in the above mentioned Brixner et al. application. The wire d3 (see Fig. 2C) extending to the storage 3-5S2 is now selectively energized in accordance with the condition of relay 8DCS1 (see Fig. 2A), energy being applied to wire d3 when the relay 8DCS1 is in its picked up position. Thus, if relay 8DCS1 is in its picked up position at this time, energy is applied to wire d3 through front contact 49 of relay 8DCS1 (see Fig. 2A), wire d2, front contact 50 of relay 8NWP, front contact 51 of relay 3-5SD2, and front contact 52 of relay 3-5TN2. Similarly, wire c3 is energized if relay 8CCS1 is picked up through front contact 53 of relay 8CCS1 (see Fig. 2A), wire c2, front contact 54 of relay 8NWP, front contact 55 of relay 3-5SD2, and front contact 56 of relay 3-5TN2. The wire b3 has energy applied thereto if relay 8BCS1 is picked up through front contact 57 of relay 8BCS1, wire b2, front contact 58 of relay 8NWP, front contact 59 of relay 3-5SD2, and front contact 60 of relay 3-5TN2.

If the route is selected over the track switch 8W in a reverse position, instead of in a normal position as has been assumed, it will be readily understood that a similar mode of operation is effective involving the energization of relays 10-12TN2 and 10-12SD2, and the transfer of route description storage to the storage unit 10-12S2 over wires b4, c4, and d4.

Relay 8DP (see Fig. 2B) is picked up upon the entrance of a car into the track section 8T by the energization of a circuit extending from (+), including front contact 61 (see Fig. 2A) of relay 8SD1, back contact 62 of relay 8TNP, back contact 63 of relay 8TR, front contact 64 of relay PD, wire 65, and winding of relay 8DP, to (-). This relay when picked up is maintained energized by a stick circuit directly dependent upon the relay 8SD1 extending from (+), including front contact 61 (see Fig. 2A) of relay 8SD1, wire 66, front contact 67 of relay 8DP, and winding of relay 8DP, to (-). The picking up of relay 8DP opens a branch of the stick circuit for relay 8SD1 at back contact 26 but the stick circuit for relay 8SD1 is maintained temporarily through back contact 31 of relay 8TR.

Relay 8DP becomes picked up at substantially the same time as the picking up of a transfer relay 3-5TN2 or 10-12TN2, and thus upon the opening of the stick circuit that has been described for relay 8SD1 by the picking up of a transfer relay TN2, a new stick circuit becomes closed through the front contact 26 of relay 8DP. Relay 8SD1 is slow enough in dropping away to bridge the cross over time of the contact 26 in shifting to select the new stick circuit. Thus, a relay 8SD1 is maintained picked up by a new stick circuit (assuming relay 3-5TN2 to be energized), extending from (+), including front contact 68 of relay 8SD1, wire 69, front contact 70 of relay 8NWP, front contact 71 of relay 3-5TN2, back contact 72 of

relay 3-5SD2, front contact 26 of relay 8DP, wire 27, contact 28 of lever 8SML, back contact 29 of relay CN, back contact 30 of relay 8CN1, and winding of relay 8SD1, to (-). When the route selection is over the track switch 8W in its reverse position, the stick circuit for the relay 8SD1 extends from (+), including front contact 68 of relay 8SD1, wire 69, front contact 73 of relay 8RWP, back contact 74 of relay 10-12SD2, front contact 75 of relay 10-12TN2, front contact 26 of relay 8DP, wire 27, contact 28 of lever 8SML, back contact 29 of relay CN, back contact 30 of relay 8CN1, and winding of relay 8SD1, to (-).

When the relay 3-5SD2 (assuming a route over track switch 8W in its normal position) becomes picked up, relay 8SD1 is deenergized by the opening of its stick circuit at back contact 72 (see Fig. 2B), but because of the slow drop away characteristics of relay 8SD1, this relay is maintained picked up long enough for the energization of the transfer circuits that have been described for transfer of the route description to the storage 3-5S2. At the end of this time interval, the relay 8SD1 is dropped away and the dropping away of this relay cancels the storage of the route description by the relays 8ACS1, 8BCS1, 8CCS1 and 8DCS1 by the opening of the stick circuits for these relays at front contact 33.

Having thus described the normal mode of operation for the automatic transfer of route descriptions as selected by the position of the track switch 8W and as rendered effective by the presence of the car in the detector track section 8T, it should be readily apparent that a similar mode of operation is effective for each of the other track switches to be encountered by the passage of a car from the hump to a predetermined classification track, this apparatus being indicated in block form according to the block diagram of Fig. 2C.

From the mode of operation of the system as it has been described, it will be apparent that the transfer of a route description is rendered effective by the picking up of a transfer relay TN upon the dropping away of a track relay TR for an associated detector track section. Thus, as has been described, a relay 3-5TN2 or 10-12TN2 is picked up in response to the dropping away of the track relay 8TR which is controlled by the track circuit for the track section 8T.

The cancellation of a route description as stored by the relays 8ACS1, 8BCS1, 8CCS1 and 8DCS1 in combination with relay 8SD1 has been described as having been rendered effective when the track relay 8TR for the associated track section 8T is dropped away after transfer of a route description has been effected. Involved in this cancellation is the picking up of relay 8DP for the apparatus associated with the track switch 8W, this relay being picked up by the closure of back contact 63 of the track relay 8TR. Relay 8DP when picked up selects a stick circuit for the storage relay 8SD1 dependent upon the front contact of a transfer relay TN and the back contact of a relay SD. If the relay 8DP were to be permitted to be picked up, at a time when no transfer relay 3-5TN2 or 10-12TN2 is picked up, it will be obvious that the relay 8SD1 would be dropped away, and thus the route description stored by the relays 8ACS1, 8BCS1, 8CCS1 and 8DCS1 would be cancelled.

From the foregoing description, it will be apparent that should the track relay 8TR, for example, be momentarily dropped away by a momentary power interruption of the power feeding its track circuit, were it not for the present invention, a route description stored by the relays 8ACS1, 8BCS1, 8CCS1 and 8DCS1, combined with relay 8SD1 would be transferred the same as if the track section 8T had become occupied by a car as has been described. This would, of course, be an improper mode of operation which might get the route description storages out of step with the cars for which they are provided. Thus, to maintain proper operation under conditions of

momentary power interruption, the power detector relay PD is provided in a manner to render the dropping away of any track relay ineffective to cause transfer or cancellation of a route description under conditions where that track relays TR are deenergized by reason of power interruption rather than by reason of their respective track circuits being shunted by the passage of cars.

The system is thus inoperative for the transfer of route descriptions while the power detector relay PD is in its dropped away position, but this relay is in its dropped away position only for the time necessary for the auxiliary power supply to take over, which is approximately 1½ seconds. This is a small fraction of the time required for a fast car to pass through the shortest track circuit, so there is no possibility of losing a transfer by the passage of a car through a detector track circuit while the auxiliary power supply is being started. In other words, if a car enters a detector track circuit while the detector relay PD is dropped away, the track relay TR for the associated track circuit will remain dropped away when the detector relay PD is picked up, and at this time transfer of the route description for the car shunting the associated track circuit will be rendered effective by the normal mode of operation. This mode of operation is also true for a car entering a track circuit substantially simultaneously with the failure of the normal power supply.

The power detector relay PD (see Fig. 2A), which is provided to prevent the above described undesirable operation upon an interruption of power, is energized whenever energy from either a normal or a standby source of alternating current is applied to the track circuits. Thus, if the track circuits are energized from the normal source of alternating current, the power detector relay PD is energized through front contacts 35 and 36 of relay PO, resistor R, and full wave rectifier 76. If the track circuits are energized from the standby source, they are energized through the back contacts 35 and 36 of the power off relay PO and thus the power detector relay PD is also energized from the standby source generator ACG when the power off relay PO is in its dropped away position. Relay PO is in its dropped away position whenever there is an interruption of the normal source of alternating current because this relay is connected directly to the normal source through the full wave rectifier 77.

With the power off relay PO in its dropped away position, direct current energy is applied through back contact 78 of relay PO to the motor M which drives the alternating current generator ACG. This generator is connected through back contacts 35 and 36 of relay PO to the respective track circuits, and also to the power detector relay PD to cause this relay to be picked up.

From the circuit organization that has been described, it will be apparent that upon an interruption of the normal source of power, the power off relay becomes dropped away. The dropping away of this relay causes the initiation of the standby motor generator and connects the output of the generator to feed the track circuits. In the time required for initiation of the motor generator, however, the power detector relay PD and the track relays become momentarily dropped away.

Because of the resistor R being connected in the circuit for the winding of the power detector relay PD, this relay is made quicker to drop away and slower to pick up than the track relays. Thus, a contact of relay PD in series with a contact of a track relay TR in a circuit can render the operation of the track relay TR effective to control the circuit except when the power detector relay PD is actuated to its dropped away position.

More specifically, for example, upon the dropping away of relay PD when there is an interruption in power feeding the track circuits, the circuit feeding the transfer relays 10-12TN2 and 3-5TN2 is opened at front contact 37 so that even though the back contact 38 of the

track relay 8TR becomes closed, neither of these transfer relays can be picked up, as is the case, according to the normal operation upon the dropping away of the track relay 8TR. Thus, there can be no transfer of route description effected when the track relay 8TR is dropped away under these conditions.

If the relay 8DP were to be permitted to be picked up under the above described conditions of power interruption in accordance with the closing of back contact 63 of track relay 8TR, the shifting of its contact 26 would open the stick circuit for the relay 8SD1 in that there could be no stick circuit closed as is provided in normal operation through a front contact of a transfer relay 3-5TN2 or 10-12TN2. It is, therefore, provided that the pick up circuit for the relay 8DP includes a front contact 64 of the power detector relay PD so that if the track relay 8TR drops away because of a power interruption, the front contact 64 of relay PD will open the circuit for relay 8DP before the circuit for this relay can be closed by the closure of back contact 63 of the track relay 8TR.

It is to be understood that the circuit associated with the other track switches are organized according to the principles that have been described with respect to the control of the relays 10-12TN2, 3-5TN2 and 8DP. This is true for each of the other track switches to be encountered in a route except the last track switch where no transfer is made and only a cancellation of the route description need be considered.

The route description for each of these last track switches is normally cancelled upon entrance of a car into the detector track section for the associated track switch by the opening of a stick circuit shown, for example, in Fig. 3 for the storage control relay 2SD1 which is associated with the track switch 2W. This relay is held up, when there is an associated storage through front contact 79 of relay 2SD1 connected in multiple with front contact 80 of relay 2TN1, front contact 81 of relay 2TR connected in multiple with front contact 82 of relay 2DP, contact 83 of relay 2SML, and back contact 84 of relay CN. To prevent the dropping away of relay 2SD1 in case front contact 81 of the track relay 2TR is momentarily opened, an auxiliary stick circuit is provided for the relay 2SD1 extending from (+), including back contact 85 of relay PD, front contact 86 of relay 2SD1, and winding of relay 2SD1, to (-). This circuit organization provides that in case the track relay 2TR is dropped away, because of a momentary power interruption of its track feed, the relay PD becomes dropped away first to close the auxiliary stick circuit so as to maintain the relay 2SD1 energized until the track relay 2TR has been restored to its picked up position by the restoration of energy to the track circuits. It is to be understood that a similar circuit organization is provided for the relays SD1 for the other track switches that are the last to be operated in a route from the hump to the different classification tracks.

Having thus described an automatic switching system for a classification yard as one embodiment of the present invention, it is to be understood that the description as set forth has been primarily for the purpose of illustrating the principles and mode of operation rather than for limiting the number of forms the present invention may assume, and it is to be further understood that various modifications, adaptations and alterations may be made with respect to the specific form shown in accordance with the requirements of practice within the scope of the appending claims.

What I claim is:

1. A railway switch control system of the character described for positioning a group of track switches in succession in a classification yard having detector track sections for the respective track switches comprising a normally active source of energy, a normally inactive

source of energy, a power-off relay energized only from said normally active source of energy, said power-off relay when deenergized being effective to render said normally inactive source active, a track circuit for each of the detector track sections having a track relay, said track circuit being energized from said normally active source of energy when said power-off relay is picked up and from said normally inactive source of energy when said power-off relay is dropped away, a power detector relay, means for energizing said power detector relay by whichever of said sources of energy that is energizing said track circuits, an independent source of energy, route description storage means for each of the track switches energized by said independent source of energy and subject to cancellation by the deenergization of the track relay for the track section of the associated track switch, and means for rendering the cancellation of said route storage means by the dropping away of the associated track relay ineffective when said power detector relay is in its deenergized position.

2. In a railway switch control system for positioning a group of track switches in succession in a classification yard having detector track sections for the respective track switches, a normally active source of alternating current, a normally inactive source of alternating current, a power-off relay energized only from said normally active source of alternating current, said power-off relay when deenergized being effective to render said normally inactive source active, a track circuit for each of the detector track sections having a track relay, said track circuit being energized from said normally active source of alternating current when said power-off relay is picked up and from said normally inactive source when said power-off relay is dropped away, a power detector relay energized by whichever of said sources of alternating current is effective for energizing said track circuits, said power detector relay being quicker to drop away when deenergized than said track relays, a source of direct current, route description storage relays for each of the track switches energized by said source of direct current and subject to cancellation by the deenergization of the track relay for the detector track section of the associated track switch, and means for rendering the cancellation of said route storage means by the dropping away of the associated track relay ineffective when said power detector relay is in its deenergized position.

3. In a railway switch control system for positioning a group of track switches in a classification yard having detector track sections for the respective track switches, a source of alternating current, a track circuit for each of the detector track sections having a track relay, said track circuit being normally energized from said source of alternating current, a power detector relay normally energized from said source of alternating current, a source of direct current, route description storage means for each of the track switches energized by said source of direct current and subject to cancellation by the deenergization of the track relay for the detector track section of the associated track switch, and means for rendering the cancellation of said route storage means by the dropping away of the track relay for the associated track switch ineffective provided that said power detector relay is dropped away.

4. A railway switch control system of the character described, for positioning a succession of track switches in a classification yard having detector track sections for the respective track switches comprising, a normally active source of energy, a normally inactive source of energy, a track circuit for each of the detector track sections having a track relay, said track circuit being energized selectively from said normally active source of energy or from said normally inactive source of energy, a power detector relay, circuit means for energizing said power detector relay from whichever of said energy sources is feeding said track circuit, an independent

source of energy, route description storage means for each of the track switches selectively energized from said independent source of energy to store a route description and subject to cancellation of a route description in response to the deenergization of the track relay for the detector track section of the associated track switch, and means for rendering the cancellation of a route description stored by said route description storage means in response to the deenergization of the track relay for the detector track section of the associated track switch ineffective when said power detector relay is in its deenergized position.

5. In a railway switch control system for positioning a succession of track switches in a classification yard having detector track sections for the respective track switches, a first source of alternating current, a second source of alternating current, a track circuit for each of the detector track sections having a track relay, said track circuit being energized selectively from said first source of alternating current or from said second source of alternating current, a power detector relay, circuit means for energizing said power detector relay from the same source of energy at all times that feeds said track circuits, route description storage means for each of the track switches effective when energized to store a route description, and transfer means for certain of the track switches for effecting the transfer of the route description stored by the associated route description storage means to the route description storage means for the next track switch in the route of a car when said track relay for the track circuit of the associated track switch is dropped away, said transfer means being ineffective upon the dropping away of the track relay for the associated track switch if said power detector relay is in its dropped away position.

6. In a railway switch control system of the character described for positioning track switches successively as a car progresses in a classification yard, a detector track section for each of the track switches, a source of alternating current, a track circuit for each of the detector track sections having a track relay and energized from said source of alternating current, a power detector relay, circuit means for energizing said power detector relay from the same source of energy that feeds said track circuits, route description storage means for each of the track switches effective when energized to store a route description, and transfer means for each of the track switches for effecting transfer of the route description stored by the associated route description storage means for the next track switch in the route of a car when said track relay for the track circuit of the associated track switch is dropped away, said transfer means being ineffective upon the dropping away of said track relay for the associated track switch if said power detector relay is in its dropped away position.

7. A railway switch control system of the character described for positioning a group of track switches successively in a classification yard having detector track sections for the respective track switches comprising, a first source of alternating current, a second source of alternating current, a power off relay energized only from said first source of alternating current, a track circuit for each of the detector track sections having a track relay, circuit means for energizing said track relay from said first source of alternating current when said power-off relay is picked up and from said second source of alternating current when said power-off relay is dropped away, a power detector relay, circuit means for energizing said power detector relay at all times from the same source of energy that feeds said track circuits, route description storage means for each of the track switches effective when energized to store a route description, and transfer means for certain of the track switches for effecting transfer of the route description stored by the associated route descrip-

11

tion storage means to the route description storage means for the next detector track switch in the route of a car when said track relay for the track circuit of the associated track switch is dropped away, said transfer means being ineffective upon the dropping away of the track relay for the associated track switch if said power detector relay is in its dropped away position.
